UNITED STATES PATENT OFFICE

SAMUEL BRAND, OF DAYTON, OHIO, ASSIGNOR TO THE NATIONAL CASH REGISTER COMPANY, OF DAYTON, OHIO, A CORPORATION OF MARYLAND

AUTOGRAPHIC REGISTER

Application filed February 25, 1927. Serial No. 170,851.

This invention relates to autographic registers and more particularly to that type which issues a double check in addition to keeping a record strip within the machine.

5 An object of the invention is to issue a double slip or check from a single strip and automatically sever the slip from the strip during the operation of the machine.

10 Another object of the invention is to provide means for controlling the feeding of both the check strip and the record strip so that they will always be uniform.

15 A further object of the invention is to provide a novel feeding device to control the issuing strip feed to render the feed ineffective when the printed forms thereon are in proper position at the writing opening.

20 Another object is to provide U-shaped slits in the issuing strip at regular intervals to control the feeding device to stop the feeding of the strips.

25 Another object is to provide a severing means located in relation to the feeding device, so that, the strip is severed across the slits in the strip.

With these and incidental objects in view, the invention includes certain novel features of construction and combinations of parts, the essential elements of which are set forth 30 in appended claims and a preferred form or embodiment of which is hereinafter described with reference to the drawings which accompany and form part of this specification.

35 Of said drawings:

Fig. 1 is a longitudinal, sectional view of the autographic register.

Fig. 2 is a top plan view of the register.

40 Fig. 3 is a view showing an original slip together with a duplicate slip printed on opposite sides of a single strip.

Fig. 4 is a detail view of the operating cam together with its cooperating members.

45 Fig. 5 is a perspective view of a section of the issuing strip, as it would appear if unwound from the supply roll, before the strip is issued from the machine, and shows the location of the U-shaped slits at regular intervals in the strip, and also shows how the 50 feeding control finger cooperates

with the U-shaped aperture to stop the feed of the strip.

Fig. 6 is a detail view of the friction drive between the main operating means and the feed rollers.

In general, the register contains a check or slip supply roll of paper having forms printed on both sides placed alternately and with a perforated line between the forms. This double slip is fed from the register and is 60 automatically severed from the strip. A separate record strip is maintained within the register. Both strips are controlled by alining devices which maintain a uniform feeding of each. The records are made upon 65 the original slip and by the aid of carbon paper duplicates are simultaneously made upon the other slip and the record strip. The strip is provided with a U-shaped slit 70 for each pair of forms printed on the slip paper, to co-act with feeding devices to control the length of feed given the issuing strip. By this means, a uniform feed is maintained for each pair of slips fed out of the machine.

75 Described in detail the register has a base 30 upon which rests a casing 31 having a writing opening 32 through which an original strip 33 is accessible for the entry of items thereon. This strip 33 is unwound 80 from a supply roll 34 and moves over a guide roller 35, across a writing table 36, around a second guide roller 37, and returns across the writing table passing between feeding rollers 38 and 39, through a slot 40 in a rigid 85 knife block 41, and out through an opening 42 in the casing 31.

The issuing check of slip strip 33 is provided with printed forms on opposite sides of the strip as shown in Figs. 3 and 5. These 90 printed forms are arranged alternately on opposite sides of the issuing strip 33, in the direction of the length of the slip having a perforated line between them so that after the slips are removed from the register they 95 may be easily separated from each other. When the original form is in position at the writing opening as shown in Fig. 2, a duplicate of this form, printed on the other side of the strip, is immediately below the orig. 100

inal form shown. As the records are entered upon this original form, duplicates are made upon the other form on the opposite side of this strip by the aid of carbon paper, which 5 is inserted between the two folds of this strip. This strip is provided with U-shaped slits (Fig. 5), placed at regular intervals, and these slits are spaced, one for each pair of printed forms, or in other words one for each 10 set of original and duplicate checks or slips. The relative position of the U-shaped slit in relation to its printed form on the strip, is clearly shown in Fig. 5.

As the strip is fed through the rollers 38 15 and 39, the slit in the strip is in alinement with a finger 48 which is held by a spring 49 against the under surface of the strip 33, and as the slit approaches the finger 48 the spring 49 will cause the finger to raise a tongue 43 20 formed by the slit and by so doing rocks a downwardly projecting arm 50 into engagement with a ratchet 51 and stops the feed of the strip 33. Fig. 5 illustrates how the feeding finger 48 raises the tongue 43 and enters 25 the strip. The ratchet 51 is freely mounted on a rod 52 and has fastened to it a gear 53 in mesh with a pinion 54 secured to the feed roller 39. Also mounted upon the rod 52 is a gear 55 which lies alongside of gear 53 and 30 drives gear 53 by a friction means so that the gear 53 can be stopped by the arm or detent 50, and the driving gear 55 continues its rotation. The friction means includes a collar 44 (Fig. 6), secured to the rod 52; a friction disk 45 loosely mounted on the rod 52, and 35 connected by a mortise and tenon to the hub of the gear 55, also loosely mounted on the rod 52; and a compression spring 46 acting to separate the friction disk 45 and gear 55 40 to create friction between the gear 53 and the friction disk 45, and between the gear 55 and collar 44, to drive the gear 53 to feed the check strip. The above described friction drive is substantially the same as that shown 45 in Letters Patent of the United States, No. 1,506,056, granted to M. M. Goldberg on August 26, 1924. In mesh with the gear 55 is a gear 56 mounted upon a shaft 57, this shaft being rotated by an operating crank 58 located 50 on the left hand side of the register, as shown in Fig. 2. The crank 58 has a plunger 59 projecting through a hand knob 60 and the end 61 of said plunger engages the lower end 55 of a yieldable stop 62 which is fastened at its upper end to the casing of the register.

As the crank 58 approaches its home position during an operation, a lug 63 on this crank engages the lower end 64 of the yieldable stop 62 to stop the crank. To start the 60 crank, the operator pushes the plunger 59 inwardly bending the yieldable stop 62 out of the plane of the lug 63.

The ratio of the gears from the operating crank to the feed rollers 39 is such that the 65 strip 33 will be moved its full distance be-

fore the operating crank has made a complete rotation, the difference of the movement being taken care of by the friction drive between the gears 53 and 55. At the beginning of an 70 operation the finger 48 is withdrawn from the path of the strip by a cam 70 which engages a pin 71 mounted in an arm 72 pinned to a shaft 73 to which the finger 48 is secured.

Near the end of an operation, the checks or slips are severed from the strip by a movable knife 74 connected by a link 75 to an arm 76 pivoted on rod 77. The arm 76 carries a roller 78 which cooperates with a cam 79 secured to the shaft 57. The knife 74 is so located in relation to the feeling finger 48, that the issuing strip is severed at a point where the U-shaped slit is located in the strip, and for this reason, when the slip is removed from the machine, the tongue 43 (Fig. 3) remains on the duplicate strip and a notch is left in the original slip. The feeling finger 48 raises the tongue 43 high enough to push the tongue out of the path of the knife, and for this reason the tongue is not severed from the strip.

It may be stated that the slits in the check strip which control the stopping of the feeding rollers may be elliptical or oblong in shape, or they may be in the form of holes and when the check is severed the cut is made 95 through a slit or perforation so that when the severed check is removed from the machine the open end of this perforation will slip over finger 48.

In addition to the original and duplicate 100 check strip there is another strip 85 which remains in the machine. This strip is fed from a supply roll 86 across the writing table 36 around a guide roller 87 and onto a receiving roll 88 which is mounted upon a shaft 89, 105 the records being made upon the strip 85 by a second sheet of carbon paper placed between strip 33 and this strip 85.

The receiving roll 88 is operated by a friction drive between the operating crank and the receiving roll. Secured to the receiving roll is a ratchet wheel 90 engaged by a pawl 91 to stop the receiving roll 88 when the right amount of paper has been moved across the writing table. The control of this stopping 110 pawl is similar to that of the check strip stopping pawl 50. This pawl 91 is mounted upon a stud 92 and fastened to a finger 93 held against the surface of the record strip 85 by a spring 94. When this finger 93 is engaging 115 the surface of the strip 85 the pawl 91 will be disengaged from the ratchet wheel 90. The record strip, like the issuing check strip, is provided with slits or holes spaced at regular intervals so that when the proper amount 120 of paper has passed over the writing table the finger 93 will enter a slit or perforation, allowing the pawl 91 to engage the ratchet wheel 90 and stop the rotation of the receiving roll 88. The pawl 91 is disengaged from 125 130

the ratchet wheel 90, and the finger 93 disengaged from the strip 85 at the beginning of an operation of the machine by a cam 96 (Fig. 4) cooperating with a pin 97 mounted in an arm 98 which is supported on the stud 92 and operatively connected to the arm 93 by a hub 99. The receiving roll 88 is rotated by the driving gear 56 through a gear 95 which lies alongside of the ratchet wheel 90 and drives this ratchet wheel by friction.

The feeding of the check strip and the record strip is always uniform as the slits or holes in these strips cooperate with the fingers 48 and 93 to correct any discrepancies due 15 to slippage, or any other cause, that may occur in the feeding of these strips during an operation of the machine.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within 25 the scope of the claims which follow.

What is claimed is:

1. In an autographic register; the combination of a pair of feed rollers to feed a record strip; means to sever the record strip 30 at regular intervals; a feeler to enter an aperture in the record strip when the aperture is adjacent the severing means; and means controlled by the feeler when the feeler enters the aperture to arrest the record strip in position to be severed at a point across the aperture.

2. In an autographic register, the combination of means to feed a record strip, said strip having at regular intervals therein a 40 slit shaped to form a tongue; severing means to cut the strip to form a separate slip; a feeler adapted to strike the tongue, raise the same out of the path of the severing means, and enter the aperture made by the removal of said tongue; means connected to and operated by the feeler, as it enters said aperture, to stop the feed of the strip with the aperture in the path of the severing means; and means to operate the severing means to cut 50 the strip on a line running across the aperture.

3. In an autographic register; the combination of means to feed a record strip; means to sever the strip at regular intervals; a device to enter an aperture in the record strip when the aperture is adjacent the severing means; means controlled by said device as the latter enters the aperture, to engage and arrest the strip feed means, whereby the strip 55 is arrested in position to be severed across the aperture; and means to disengage the last-named means from the strip feed means and remove said device from the path of the strip.

4. In an autographic register; the combination of means to feed a record strip; means

to sever the strip; a device to enter an aperture in the record strip at a predetermined point; a detent connected to said device and adapted to engage the strip feed means to arrest the strip so that the severing means 70 operates on the strip across the aperture; and means to control the detent to disengage the detent from strip feed means, and to control the device to remove the device from the aperture in the strip.

5. In an autographic register; the combination of means to feed a record strip; means to sever the strip at regular intervals; and means, yieldingly actuated in one direction to enter an aperture in the record at a predetermined point, and to engage the strip feed means to arrest the strip so that the severing means operates on the strip across the aperture, said last-named means being positively actuated in another direction to be 85 withdrawn from the aperture and disengaged from the strip feed means.

6. In an autographic register; the combination of a pair of feed rollers to feed a record strip, said strip having apertures cut to 90 form tongues; means to sever the strip at regular intervals; a feeler to enter one of the apertures as the strip is fed, feed roller arresting means connected to the feeler to be actuated thereby to arrest the strip when the 95 aperture into which the feeler is projected, is adjacent the severing means; and means to actuate the severing means when the aperture is adjacent thereto, to cut the strip across the aperture to form a slip with a tongue at one 100 end and a notch at the other end.

In testimony whereof I affix my signature,
SAMUEL BRAND.
